Primary Examiner — Nathaniel D. Buckner*(74) Attorney, Agent, or Firm* — TraskBritt**(57) CLAIM**

The ornamental design for an electric actuator, as shown and described.

DESCRIPTION

FIG. 1 is a top, rear left perspective view of the design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is another perspective view thereof; and,

FIG. 10 is another perspective view thereof.

The broken lines in FIGS. 1-10 illustrate portions of the electric actuator that form no part of the claimed design.

1 Claim, 10 Drawing Sheets(56)
